US00D761228S

(12) **United States Design Patent**
Cho et al.

(10) **Patent No.:** **US D761,228 S**
(45) **Date of Patent:** **** Jul. 12, 2016**

(54) **SPEAKER**

- (71) Applicant: **Samsung Electronics Co., Ltd.**, Suwon-si, Gyeonggi-do (KR)
- (72) Inventors: **Chulyong Cho**, Seoul (KR); **Min Hee Lee**, Seoul (KR); **Min Joon Jung**, Seoul (KR); **Kyoung Hoon Kim**, Seongnam-si (KR)
- (73) Assignee: **SAMSUNG ELECTRONICS CO., LTD. (KR)**
- (**) Term: **14 Years**

(21) Appl. No.: **29/497,830**

(22) Filed: **Jul. 29, 2014**

(30) **Foreign Application Priority Data**

Jan. 29, 2014 (KR) 30-2014-0005052

(57) **CLAIM**

The ornamental design for a speaker, as shown and described.

DESCRIPTION

FIG. 1 is a front perspective view of a speaker, showing our new design;

FIG. 2 is a front view thereof;

FIG. 3 is a rear view thereof;

FIG. 4 is a side view thereof;

FIG. 5 is another side view thereof;

FIG. 6 is a top plan view thereof;

FIG. 7 is a bottom plan view thereof; and,

FIG. 8 is another perspective view thereof, as shown in use.

The broken line portions of FIGS. 1-8 are included to show unclaimed subject matter only and form no part of the claimed design.

1 Claim, 8 Drawing Sheets
